UNITED STATES PATENT OFFICE.

GREEN T. KEE, OF KANSAS CITY, MISSOURI.

CLOTHES DRIER.

Application filed April 18, 1923. Serial No. 331,827.

To all whom it may concern:

Be it known that I, GREEN T. KEE, a citizen of the United States, residing at Kansas City, in the county of Jackson and State of Missouri, have invented certain new and useful Improvements in Clothes Driers; and I do declare the following to be a full, clear, and exact description of the invention, such as will enable others skilled in the art to 10 which it appertains to make and use the same, reference being had to the accompanying drawings, and to the figures of reference marked thereon, which form a part of this specification.

15 This invention relates to clothes driers and the primary object thereof is to provide an improved form of clothes drier so constructed that the clothes may be contained within a clothes chamber through 20 which atmospheric air may pass, the air being heated by a heater having ducts surrounding the clothes chamber but in communication therewith. This is important since the clothes will absorb the fumes of 25 the products of combustion wherever they come into contact and experience has taught that wherever the products of combustion contact with the clothes, the clothes show the result of such contact, particularly if white 30 goods is being dried.

It is an important feature of my invention that the flow through the heating ducts be relatively slow to permit the clothes chamber to absorb the maximum B. t. u.'s from 35 the products of combustion before they pass to atmosphere.

It is understood that only atmospheric air comes into contact with the clothes from which the moisture is being evaporated. 40 Therefore, the heated atmosphere has a more or less sterilizing effect on the clothes and leaves them sweet and clean when they are taken from the clothes chamber.

I have provided means for retarding the 45 flow of the products of combustion through the heating ducts and these can be so arranged that the rate of flow of the heated air can be such that the maximum efficiency will result.

50 I have also constructed the clothes drier so that the clothes chamber will be uniformly heated throughout, this being important so that all of the clothes can be dried at the same time rather than to have local application of heat at different parts of the

clothes chamber, it being apparent that if the clothes chamber had variable heat zones, some of the clothes would dry while the others would still remain wet. Such a device would be unsuitable for practical use. 60

I have also provided means whereby the clothes can be introduced into the clothes chamber in a convenient manner, there being racks in the clothes chamber which may be extended outside the drier to receive the 65 clothes preparatory to their introduction into the drier.

The novel construction of the invention will be apparent by reference to the following description in connection with the accompanying drawings, in which—

Fig. 1 is a perspective view of a clothes drier constructed in accordance with my invention, parts being broken away to show the heat ducts, the air inlets for the combustion chamber, and the rack for holding 75 the clothes.

Fig. 2 is a fragmentary, perspective view of a rack bar and its support.

Fig. 3 is a vertical, longitudinal, sectional view through the drier.

Fig. 4 is a cross sectional view through the drier, and

Fig. 5 is a fragmentary, sectional view of the rack bar support.

The casing is shown as substantially rectangular having sides 1 and 2, a back 3 and an open front 4, adapted to be closed by the doors 5 and 6. The doors may be fastened by suitable bolts 7 and 8 operated by a 90 swinging throw lever 9 controlled from the outside of the drier.

The drier is also provided with a top 10 having an elongated slot or opening 11 covered by a deck 12 spaced away from the top 95 so that outlet openings or spaces 13 and 14 are provided.

Within the casing is a clothes chamber 100 also substantially rectangular. It consists of side walls 15 and 16, and an open front 4 and is accessible through the opening 4 closed by the doors 5 and 6. The top 18 of the clothes chamber is provided with a longitudinally disposed opening or slot 19 in line with the slot 11 so that the air passing 105 through the clothes chamber can also exhaust through the openings 13 and 14. The walls 15 and 16 of the clothes chamber extend from the front to the rear of the casing and they are spaced from the walls 1 110

and 2 to provide longitudinal spaces 20 and 21 which are co-extensive with the length of the drier.

The bottom 22 of the clothes chamber is located a substantial distance above the bottom 23 of the casing to provide a space divided into two subjacent chambers 24 and 25. The subjacent chamber 25 is the combustion chamber and it has located therein a burner 26, by means of which the bottom of the chamber 24 can be heated. The bottom 23 for the combustion chamber is provided with a plurality of air inlet openings 27, admitting only enough air to support combustion. This air is heated in the combustion chamber 25 and slowly passes up the ducts or spaces 20 and 21 and out through the converging spaces 29 and 30 to the exhaust spaces 13 and 14.

20 The top of the clothes chamber converges slightly toward the top of the casing so that the spaces 29 are slightly restricted to tend to hold back the products of combustion and, therefore, retain them for the maximum time in the ducts, allowing the air in the clothes chamber to absorb the maximum amount of heat to evaporate the moisture from the clothes.

30 The bottom 31 of the fresh air chamber 24 is provided with upwardly converging portions 32 and 33 against which the products of combustion first contact so that the hottest part of the bottom of the fresh air chamber will be at the center.

35 The ends of the casing are provided with fresh air inlet openings 34 and 35 whereby fresh air may be admitted into the fresh air chamber 24 and then pass through the openings 36 in the bottom plate 22 of the clothes chamber. The fresh air passes up through the bottom of the clothes chamber and contacts with the clothes supported on the drying racks and then passes out through the port 19.

40 The clothes can be supported on a rack structure consisting of a triangular bracket having downwardly converging frame members 38 and 39 at one end and 40 and 41 at the other. The members 38 and 40 are connected by guide rods 42 and the members 39 and 41 are connected with similar longitudinal guide rods 43. These support the clothes-supporting bars. The clothes-supporting bars are designated 44 and they 45 carry hooks 45 and 46. The hooks 45 may be closed around the supporting guide rods 42. The hooks 46, however, will be open to engage over the hooked ends 47 of the rods 42 so that the hooks 46 can be removed from the ends 47 to permit the clothes-supporting rods or bars 44 to be slid outwardly through the opening in the drier.

I have provided a bar-supporting rack for holding the bars 44 in their extended positions when the clothes are being dried.

This rack consists of telescoping members 48 and 49, the member 49 being slidable in a tubular guide 50 fastened to the top of the clothes chamber. Depending from the outer end of the telescoping member 49 is a rack 70 bar 51 having projections 52 thereon, over which the hooks 46 may engage when the parts are extended as shown in Fig. 1. The member 49 carries a head 53 at its inner end which is adapted to abut against the shoulder 54 on the end of the tubular guide 50 so that the member 49 cannot be pulled out of the guide 50 which is shown in Fig. 5.

75 When the parts are assembled and the burner is lighted, the doors 5 and 6 will be opened, the clothes bar-supporting rack will be extended as shown in Fig. 1 and one of the bars 44 will be drawn out to the position shown in Fig. 1 with its forward ends supported on one of the projections 52. The clothes will then be applied to the bar 44, the bar will be slid back into the drier and the hook 46 will be hooked on one of the projections 47. Then another bar 44 will be extended to receive the clothes and in this way the clothes-supporting rack will be filled. Then the clothes bar supporting rack will be pushed back into the drier and the doors closed. The heat generated in the combustion chamber 25 will pass up through the ducts 20 and 21 at a relatively slow rate and the products of combustion will be slowly choked between the two top members 18 and 10 so that the rate of flow of the air through the ducts 20 and 21 will be relatively sluggish. This will give the air coming through the ports 34 and 35 and through the openings 36 time enough to absorb the heat through the walls 15 and 16 so that the air will be heated. Since the products of combustion will completely surround the clothes chamber 17, all of the parts of the clothes chamber will be uniformly heated and the hot air will pass through the clothes and out through the neck or opening 19. During the passage of the heated air, the moisture will be evaporated from the clothes and in a relatively short time, the clothes will be completely dried.

100 105 110 115 120 125 130 Since the products of combustion do not come into contact with the clothes, it is obvious that they will not have the odor of the burnt gases and I have found in actual experience that by segregating the products of combustion from the air which comes into contact with the clothes, white clothes bleach out without any appearance of "yellowness" which is sometimes observed in clothes dried by artificial means.

The air removes any odor from the clothes as all of the wash water is evaporated and the fact that fresh air passes through the clothes after they are dried and at a high temperature insures their being thoroughly aerated and practically sterilized.

The device is simple in construction, inexpensive to manufacture and will efficiently perform the functions for which it is intended.

5. What I claim and desire to secure by Letters-Patent is:

1. A clothes drier comprising a casing, a clothes chamber within the casing, the side walls of which are spaced from the casing 10 to provide ducts, a bottom in the casing spaced from the bottom of the clothes chamber and having openings for the admission of air to support combustion only, a burner between the bottom of the clothes drier and the bottom of the casing, and a perforate bottom in the clothes chamber above the normal bottom to provide a space, the space 15 communicating with atmosphere whereby atmosphere can pass into the space and through the perforate bottom into the clothes chamber to aerate the clothes, the tops of the casing and the clothes chamber having aligning openings communicating with atmosphere.
2. A clothes drier comprising a casing having a perforate bottom, the perforations in the bottom being sufficient to admit air for the support of combustion only, a clothes chamber comprising an inner casing having 20 an imperforate bottom and side walls spaced from the casing, the top of the clothes chamber having an opening aligning with an opening in the top of the casing, the side walls of the clothes chamber being 25 spaced from the side walls of the casing to provide ducts for the passage of the products of combustion, the upper portions of the ducts being constricted to cause the passage of the products of combustion to flow 30 sluggishly, and means for admitting air directly to the clothes chamber.
3. A clothes drier comprising a casing,

an inner casing having a portion spaced from the outer casing to provide a combustion chamber between the inner casing 45 and the bottom of the outer casing, the bottom of the inner casing consisting of an imperforate sheet, the inner casing having a perforate false bottom above the normal bottom, the walls of the inner casing in the 50 space between the normal bottom and perforate bottom being provided with perforations whereby atmosphere may enter the space between the perforate and imperforate bottoms of the inner casing, the space 55 between the top of the inner casing and the top of the outer casing being restricted and the tops of both the inner and outer casings being provided with openings.

4. A clothes drier comprising a casing, 60 means for heating it, and a clothes rack in the casing comprising a bracket, a plurality of longitudinally slideable clothes supporting members carried by the bracket, each member having an end removably engaging the bracket and a longitudinally slideable support movable beyond the bracket and having members to support the free ends of the clothes-carrying members.

5. A clothes drier comprising a casing 70 having a clothes chamber, a V-shaped frame in the upper end of the clothes chamber including a plurality of spaced, horizontal rods, clothes supporting members slideable on said rods, each clothes supporting member having one end removably from engagement with the frame, and a longitudinally slideable supporting member carried within the clothes chamber and having means for engagement by the free ends of the clothes 75 supporting members.

In testimony whereof I affix my signature.

GREEN T. KEE.
